Des. 951

Nicholas Muller, of New York, N. Y.
Letters Patent No 951. Dated Oct 13th 1857

The schedule referred to in these Letters Patent of making part of the same

To all whom it may concern:

Be it known that I, Nicholas Muller, of the City, County and State of New York, have invented or produced a new and original design for the fronts of block cases, and I do hereby declare that the following is a full & exact description of the same, reference being had to the accompanying drawings, and to the letters of reference marked thereon.

Fig: 1. represents a full front view of the clock case.

Fig: 2. a side view taken from the right of the case, and

Fig: 3. shows a transverse horizontal section in the line x. y. of fig: 1.

The pedestal as shown in fig: 1. consists of 3 curved fields: the middle one a, retreating in symmetrical line from the projecting side fields is ornamented by a wreath of flowers, and bears the pendulum hole, vertically below the dial hole c. On the right side above the pedestal is the figure of a child in sitting posture, one arm rests on the frame of the pendulum hole and holds a helical snail, the other extended arm bears moss and flowers: the head of the child reclines on flowerbuds, above which rises up an ornamental wreath composed of the leaves, ears & blossoms of water plants and reeds, clinging around the frame of the

Des. 957

dial hole c.

The left side is formed by the figure of a boy e. e. holding to the frame, with a shepherd's hat, his right foot resting on the frame for the pendulum hole, his left foot is half hidden by leaves and shells which surmount the left field of the pedestal.

The ornament on the top of the whole case is a vase, formed by three shells bearing an univalve shell with large dents.

What I claim as my invention & wish to secure by Letters Patent is,

The ornamental pedestal, the two figures d and e resting on its sides, the wreath surrounding the frame of the dial hole and the top-ornament f. all as represented in the drawing.

The whole forming a design for a block-case
